CLAIM

The ornamental design for a fryer heat exchange tube, as shown and described.

DESCRIPTION

FIG. 1 is a perspective view of a fryer heat exchange tube showing my new design;

FIG. 2 is top view of the fryer heat exchange tube of FIG. 1; FIG. 3 is a front view of the fryer heat exchange tube of FIG. 1;

FIG. 4 is a rear view of the fryer heat exchange tube of FIG. 1;

FIG. 5 is bottom view of the fryer heat exchange tube of FIG. 1; and,

FIG. 6 is a side view of the fryer heat exchange tube of FIG. 1.

The broken lines shown in the drawings are for illustrative purposes only and form no part of the claimed design.
